UNITED STATES PATENT OFFICE.

PERRY BROWN, OF CORAOPOLIS, PENNSYLVANIA.

DRAFT-RIGGING.

1,299,114.

Specification of Letters Patent.

Patented Apr. 1, 1919.

Application filed August 5, 1915. Serial No. 43,881.

To all whom it may concern:

Be it known that I, PERRY BROWN, a citizen of the United States of America, and a resident of Coraopolis, in the county of Allegheny and State of Pennsylvania, have invented certain new and useful Improvements in Draft-Rigging, of which the following is a specification.

This invention relates to improvements in draft rigging for cars and the object of the invention is to provide a simple rigging of large capacity and one which will be capable of receiving the heavy shocks necessary to be sustained by car riggings in the present day service.

The invention consists in the construction and arrangement of parts hereinafter more fully described and then definitely claimed.

In the drawings accompanying and forming part hereof:

Figure 1 is a horizontal section of my draft rigging taken lengthwise thereto.

Fig. 2 is a horizontal section of the main casting connected with the draw bar.

Fig. 3 is a perspective view of the cap plate detached.

Fig. 4 is a longitudinal vertical section at right angles to that shown in Fig. 1.

Fig. 5 is a perspective view of a casting shown in Fig. 2, together with its locking device separated.

Fig. 6 is a section taken through the line 6—6 of Fig. 1.

Fig. 7 is a sectional view taken through the line 7—7 of Fig. 1.

Referring now to the details of the drawings by numerals: 1 and 2 designate a pair of draft irons secured between the end sill 3 and the bolster 4, these draft irons being provided with forward abutments 8, intermediate abutments 10 and rear abutments 12. The draft irons are also formed on their exterior walls with reinforcing lugs 16 and the draft irons and their lugs are slotted as indicated in dotted lines at 18 in Fig. 1 for a purpose to be hereinafter explained.

Between the draft irons is located a container for the main springs, this container being preferably a large heavy casting and is illustrated in Figs. 2 and 5. As shown, this container has two pockets 20 and 22 to contain the springs and its other end forms a socket to receive the shank of the draw bar. On its sides the container is formed with two sets of projections 24 and 26, these projections being located between the forward

abutments 8 and the intermediate abutments 10 of the draft irons 1 and 2 and coact therewith. will be hereinafter explained. The socket to receive the shank of the draw bar 60 comprises a recess 28 and the shank 30 of the draw bar is inserted in this recess so that its upper horizontal rib or shoulder 32 will fit into the upper end of the recess as clearly shown in Fig. 4. After the shank is 65 placed in this position, a securing plate 36 is slipped through the opening 38, shown in Figs. 4 and 5, up into the space between the bottom rib or shoulder 34 of the draw bar shank and two lugs 40 and 41 cast on the 70 front end of the socket so that this plate 36 will form a lock between the shoulder 34 and said lugs 40 and 41. After the plate 36 is in position, a locking key 42 is inserted in the passage 38 immediately under the aforesaid plate 36, this key holding the plate 36 75 in its locking position. After the key 42 is placed in position, a bolt 44 is inserted through ears 46 cast on the socket, this bolt co-acting with a lug 48 on the key 42 and thereby holding all the parts in their proper 80 positions. The socket 28 is formed with diverging walls as shown in Figs. 1 and 2, so that there is a slight space between the rear end of the shank 30 and the walls of the 85 socket in order to provide slight movement therein when the cars are taking a curve.

The container is slotted horizontally as indicated at 50, 52, 54 and 56, the slots 50 and 52 being in alinement with each other 90 and the slots 54 and 56 also being in alinement. These slots are for the purpose of receiving horizontal plates or bars 58, 59, 60 and 61 which co-act with the abutments 8 and 10 of the draft irons hereinbefore referred to. The first three of these bars 58, 59 and 60 are of the exact length to fill the space between the interior walls of the draft irons 1 and 2, but the fourth plate, 61, in addition to passing through the slots 56 of 95 the container, is long enough to pass through slots in the draft irons and in the reinforcing lugs 16, the plate 61 being secured in position by means of a pin 70 and cotter 72.

In assembling my rigging, the plates 58 and 60 are first placed through the slots 50 and 54 of the container; the two sets of springs are then placed within the openings of the container, the upper plate 59 is placed through its slot 52 and the rigging is then 100 inserted from below upward between the draft irons 1 and 2, and secured in this posi-

tion by the plate 61 which is passed through the slots in the draft irons and the slots 56 in the container. The draw bar may be secured in the socket of the container either 5 before or after the container is placed in its position as above described.

In operation, on an impact the coupler forces the container backward, carrying with it the front horizontal plates 58 and 10 60 and these bearing against the two sets of springs compress said two sets of springs against the rear horizontal plates 59 and 61 which are held against rearward movement by means of the abutments 10. On a pull, 15 the shank of the draw bar being held in its pocket in the container by means of the locking plate 36 and key 42, the container is drawn to the front, drawing with it the rear plates 59 and 61, thereby compressing the two 20 sets of springs within the container against the forward plates 58 and 60 which are now held from forward movement by means of the abutments 8.

In order to supplement this rigging on an 25 impact, I also provide a second set of springs designated 70 and 71, which are contained within pockets formed in a block 72 held between the draft irons 1 and 2 by means of the rear abutments 12 hereinbefore described. 30 When these springs 70 and 71 are used to supplement the main rigging I employ a double plate 74 which is interposed between the end of the container and the springs 70 and 71, this double plate having two horizontal ribs 76 and 77 and two small lugs 78 and 79 which project into the container. The walls 80 and 81 forming the pockets for the springs 70 and 71 project just the proper distance to be struck by the plate 74 35 on an impact whereby the load is taken off of the springs and the springs prevented from crowding.

It will be obvious that changes and modifications may be made in the rigging which 45 is shown in its preferable embodiment in the accompanying drawings and reference should therefore be made to the appended claims to determine the scope of the invention.

50 What I claim as my invention is:

1. In a draft rigging and in combination with the draw bar and draft irons having abutments, a container comprising an integral member having two sets of springs vertically disposed therein at one end of the 55 container and a socket at the other end of the container to receive the shank of the draw bar, horizontal plates or bars on opposite ends of said two sets of springs co-acting with the abutments on said draft irons, and projections on the exterior of 60 said container located between the abutments of the draft irons and adapted to contact with said abutments to prevent the springs 65 from being driven beyond their capacity.

2. In a draft rigging and in combination with the draw bar and draft irons having abutments, a container comprising an integral member having two sets of springs vertically disposed therein at one end of the 70 container and a socket at the other end of the container to receive the shank of the draw bar, horizontal plates or bars on opposite ends of said two sets of springs co-acting with abutments on said draft irons, one of said horizontal plates connecting the draft irons and supporting the container and springs and the other of said horizontal plates bridging the space between said draft irons without passing through said irons, and projections on the exterior of said container located between the abutments of the draft irons and adapted to contact with said abutments to prevent the springs from 75 being driven beyond their capacity. 80

3. In a draft rigging and in combination with the draw bar and draft irons having abutments, a container comprising an integral member having two sets of springs vertically disposed therein at one end of the 90 container and a socket at the other end of the container to receive the shank of the draw bar, and horizontal plates or bars on opposite ends of said two sets of springs co-acting with the abutments on said draft irons, three of said horizontal plates or bars resting between said abutments and the fourth plate passing through slots in the draft irons and thereby supporting the container and springs. 95

4. In a draft rigging and in combination with the draw bar and draft irons having abutments, a container comprising an integral member having two sets of springs vertically disposed therein at one end of the container and a socket at the other end of the container to receive the shank of the draw bar, horizontal plates or bars on opposite ends of said two sets of springs co-acting with the abutments on said draft irons, three of said horizontal plates or bars resting between said abutments and the fourth plate passing through slots in the draft irons, and thereby supporting the container and springs, and projections on the exterior of 100 said container located between the abutments of the draft irons and adapted to contact with said abutments to prevent the springs from being driven beyond their capacity. 110

5. In a draft rigging and in combination with the draw bar and draft irons, a container comprising an integral member having two sets of springs vertically disposed therein at one end of the container and a socket at the other end of the container to receive the shank of the draw bar, an additional spring support located between said draft irons in the rear of said container, springs carried by said support and receiv- 115 120 125 130

- ing the thrust from said container on an impact, and a plate located on the end of said container and in front of said springs.
6. In a draft rigging and in combination 5 with the draw bar and draft irons, the latter having front, intermediate and rear abutments, a container comprising an integral member having two sets of springs therein at one end of the container and a socket at 10 the other end of the container to receive the shank of the draw bar, two sets of springs in said container, horizontal bars or plates on opposite sides of said springs passing through the container and co-acting with the 15 front and intermediate abutments, an additional spring support backing up against the rear abutments, and springs carried by said support and receiving the impact from the container.
- 20 7. In a draft rigging and in combination with the draw bar and draft irons, the latter having front, intermediate and rear abutments, a container comprising an integral member having two sets of springs therein 25 at one end of the container and a socket at the other end of the container to receive the shank of the draw bar, two sets of springs in said container, horizontal bars or plates on opposite sides of said springs passing 30 through the container and co-acting with the front and intermediate abutments, an additional spring support backing up against the rear abutments, springs carried by said support and receiving the impact from the container, and a plate located on the end of said 35 container and in front of said springs and transmitting the blow from the container to the springs.
8. In a draft rigging and in combination with the draw bar, a container comprising 40 an integral casting and having two vertically disposed pockets therein for the reception of springs, two sets of horizontal slots in said container for the passage of bars, and a socket on the front end of said container to 45 receive the draw bar shank.
9. In a draft rigging and in combination with the draw bar, a container comprising an integral casting and having two vertically 50 disposed pockets therein for the reception of springs, two sets of horizontal slots in said container for the passage of bars, a socket on the front end of said container to receive the draw bar shank, and two sets of projections on opposite sides of the container 55 adapted to co-act with abutments of the draft irons to prevent the springs from being driven beyond their capacity.
10. In a draft rigging, a container comprising an integral casting having two sets 60 of vertically disposed pockets therein for the reception of springs, two sets of horizontal slots for the passage of bars, and two sets of projections on the sides of said container 65 adapted to co-act with abutments on the draft irons to prevent the springs from being driven beyond their capacity, the ends of the aforesaid slots being farther apart than the said projections.

In testimony whereof I affix my signature 70
in presence of two witnesses.
